Filed Aug. 31, 1926

INVENTOR:

Geoffrey L. Pilkington
BY *Rogers, Kennedy, Campbell*
Attn:

UNITED STATES PATENT OFFICE.

GEOFFREY LANGTON PILKINGTON, OF ST. HELENS, ENGLAND, ASSIGNOR TO PILKINGTON BROTHERS LIMITED, OF LIVERPOOL, ENGLAND, A BRITISH COMPANY.

DESIGN FOR CATHEDRAL GLASS.

Application filed August 31, 1926, Serial No. 18,910, and in Great Britain July 21, 1926. Term of patent, 14 years.

To all whom it may concern:

Be it known that I, GEOFFREY LANGTON PILKINGTON, a British subject, and resident of St. Helens, in the county of Lancaster, England, have invented a new, original, and ornamental Design for Cathedral Glass, of which the following is a specification, reference being had to the accompanying drawing, forming part thereof.

The drawing is a perspective view of a portion of cathedral glass showing my new design.

I claim:

The ornamental design for cathedral glass as shown.

GEOFFREY LANGTON PILKINGTON.
